CLAIM

The ornamental design for an automotive carburetor repair tool, as shown and described.

DESCRIPTION

FIG. 1 is a front elevational view of the automotive carburetor repair tool showing a first embodiment of my new design, the rear view being identical;
FIG. 2 is a side elevational view thereof, the opposite side being identical;

FIG. 3 is a top plan view thereof;

FIG. 4 is a bottom plan view thereof;

FIG. 5 is a front elevational view of the automotive carburetor repair tool showing a second embodiment of the socket portion of my new design; the handle being omitted for ease of illustration only;

FIG. 6 is a rear elevational view thereof; and

FIG. 7 is a bottom plan view thereof.

FIG. 1

FIG. 2

FIG. 3

FIG. 5

FIG. 7

FIG. 4

FIG. 6
